(57) **CLAIM**

The ornamental design for a motor for railway vehicle, as shown and described.

DESCRIPTION

FIG. 1. is a front perspective view of the front, right, and top sides of a motor for railway vehicle showing my new design; FIG. 2. is a rear perspective view of the rear, left, and bottom sides thereof;

FIG. 3. is a front view thereof;
FIG. 4. is a rear view thereof;
FIG. 5. is a top plan view thereof;
FIG. 6. is a bottom view thereof;
FIG. 7. is a right side view thereof; and,
FIG. 8. is a left side view thereof.

The broken lines shown represent portions of the motor for railway vehicle and form no part of the claimed design.
